UNITED STATES PATENT OFFICE.

JOHN B. COXON, OF KOKOMO, INDIANA, ASSIGNOR TO KOKOMO SANITARY POTTERY COMPANY, OF KOKOMO, INDIANA.

DESIGN FOR A CLOSET BOWL.

Application filed September 21, 1926. Serial No. 19,128. Term of patent 14 years.

To all whom it may concern:

Be it known that I, JOHN B. COXON, a citizen of the United States, residing at Kokomo, in the county of Howard and State of Indiana, have invented a new, original, and ornamental Design for a Closet Bowl, of which the following is a specification, reference being had to the accompanying drawing, forming a part thereof.

Figure 1 is a top plan view of a closet bowl showing my new design,

Figure 2 is a side elevation thereof,

Figure 3 is a front elevation thereof,

Figure 4 is a rear elevation of the bowl, and

Figure 5 is a bottom plan view of the bowl.

The distinguishing features of the design are the main base plate having flat marginal faces with upper edges beveled and the offset sub-base supporting the stand for the bowl. The stand in turn embodies a front inwardly tapered portion having flat front and side faces which taper inwardly toward the bowl, which faces merge in with the faces of the sub-base.

I claim:

The ornamental design for a closet bowl, as shown and described.

JOHN B. COXON.
